UNITED STATES PATENT OFFICE.

WINFIELD J. ABRAHAMS, OF BALTIMORE, MARYLAND.

RAILROAD-SPIKE.

1,303,002.

Specification of Letters Patent.

Patented May 6, 1919.

Application filed May 18, 1918. Serial No. 235,314.

To all whom it may concern:

Be it known that I, WINFIELD J. ABRAHAMS, a citizen of the United States, residing at Baltimore, State of Maryland, have 5 invented certain new and useful Improvements in Railroad-Spikes; and I do hereby declare the following to be a full, clear, and exact description of the invention, such as will enable others skilled in the art to which 10 it appertains to make and use the same.

This invention relates to improvements in railroad spikes and has for one of its objects the provision of a device of this character whereby upon rotation or turning of 15 the same after being driven into a tie, it will be firmly held against withdrawal from the tie.

Another object of this invention is the provision of means for limiting the movement of the spike into the tie so that the 20 same can be readily turned for locking it against withdrawal from the tie.

A further object of this invention is the provision of a railroad spike of the above 25 stated character which shall be simple, durable and efficient, and which may be manufactured and sold at a comparatively low cost.

With these and other objects in view as 30 will become more apparent as the description proceeds, the invention consists in certain novel features of construction, combination, and arrangement of parts as will be hereinafter more fully described and 35 claimed.

For a complete understanding of my invention, reference is to be had to the following description and accompanying drawing, in which:

40 Figure 1 is a top plan view of a railroad spike illustrating the same applied to a tie and railroad rail and constructed in accordance with my invention,

Fig. 2 is a transverse sectional view of 45 the same,

Fig. 3 is a fragmentary perspective view of the spike,

Fig. 4 is a transverse sectional view taken on the line 4—4 of Fig. 2.

50 Referring in detail to the drawing, the numeral 1 indicates a railroad tie having mounted thereon a railroad rail 2. A cylindrical shank 3 has formed upon one end thereof a driving head 4 while its opposite 55 end is tapered as illustrated at 5 to form a driving point. The tapered end 5 is of a

substantially conical shape as clearly illustrated in Fig. 2 for the purpose of aiding in driving the shank 3 into the tie 1. The shank 3 adjacent the tapered portion 5 is 60 provided with oppositely disposed flattened surfaces 6 and with oppositely disposed series of screw threads 7. These screw threads 7 are so arranged upon the shank 3 that they are adapted to bite or cut into the tie upon 65 rotating the shank 3 whereby the shank is firmly locked into the tie.

The head 4 is of such a shape that the same projects laterally of the shank 3 for the purpose of engaging the base 8 of the 70 railroad rail 2 as clearly illustrated in Fig. 2. An extension 9 is formed upon the laterally projecting end of the head 4 and is adapted to overlie and rest upon the base 8 of the railroad rail 2 when the spike or shank 75 3 is in its rail securing position. The upper face of the extension 9 is convexed while the bottom face is beveled to conform to the inclination of the base 8 of the rail 2. A lateral nib 10 is formed upon one edge of 80 the extension 9 at its free end and is adapted to limit the movement of the spike or shank 3 into the tie 1 during the first securing operation of the spike into the tie.

In operation, the shank 3 is driven into 85 the tie 1 by a suitable tool with the extension 9 disposed parallel with the railroad rail 2 as illustrated in full lines in Fig. 1 and as the shank 3 reaches home in the tie, the nib engages the base of the rail thereby 90 limiting further movement of the shank into the tie. A wrench or suitable tool is then placed upon the head 4 and turned so that the extension 9 and laterally projecting end 95 of the head 4 is disposed over the base of the rail 2 and by so doing causes the threads 7 to bite into the tie locking the shank 3 firmly thereto. By having the nib 10 resting upon the base 8 of the rail 2 before 100 turning of the shank 3 provides means whereby the extension 9 will be guided over the base 8 of the rail 2 when the shank 3 is turned. In order to remove the spike or shank 3 from the tie 1, the shank 3 is turned in a reverse direction placing the 105 threads 7 in alignment with the path that they made when the shank was driven into the tie, so that the spike or shank can be readily withdrawn from the tie.

While I have shown and described the 110 preferred embodiment of my invention, it will be understood that minor changes in

construction, combination, and arrangement of parts may be made without departing from the spirit and scope of the invention as claimed.

- 5 Having thus described my invention, what I claim is:—

A railroad spike comprising a shank having a tapered end, opposite disposed screw threads formed upon said shank and adapted to bite into a tie upon turning the shank in the tie after being driven into said tie, flattened portions mounted upon said shank between said screw threads, a head formed

upon said shank, a lateral extension formed upon said head and adapted to overlie the base of a railroad rail, and means formed upon said extension for engagement with the base of the rail prior to turning the shank to cause the threads to bite into the tie.

In testimony whereof I affix my signature in presence of two witnesses.

WINFIELD J. ABRAHAMS.
